(57) CLAIM

The ornamental design for a clipper holder, as shown and described.

DESCRIPTION

FIG. 1 is a perspective view of the clipper holder.

FIG. 2 is a front elevational view of the clipper holder of FIG. 1.

FIG. 3 is a back view of the clipper holder of FIG. 1.

FIG. 4 is a right side view of the clipper holder of FIG. 1.

FIG. 5 is a left side view of the clipper holder of FIG. 1.

FIG. 6 is a top view of the clipper holder of FIG. 1; and, FIG. 7 is a bottom view of the clipper holder of FIG. 1.

The broken lines appearing in the figures are for the purpose of illustrating the structure of the article of the claimed design and form no part of the claimed design.
